UNITED STATES PATENT OFFICE.

ARTHUR J. ARCHAMBAULT, OF CHICAGO, ILLINOIS.

PLUMBER'S FURNACE.

1,090,009.

Specification of Letters Patent. Patented Mar. 10, 1914.

Application filed October 3, 1913. Serial No. 793,239.

To all whom it may concern:

Be it known that I, ARTHUR J. ARCHAMBAULT, a citizen of the United States, residing at Rogers Park, Chicago, in the county 5 of Cook and State of Illinois, have invented new and useful Improvements in Plumbers' Furnaces, of which the following is a specification.

This invention relates to plumbers' furnaces and it consists in the novel features hereinafter described and claimed.

An object of the invention is to provide a furnace of the nature indicated especially adapted for plumbers' uses.

15 In the accompanying drawing:—Figure 1 is a side elevation of the furnace with parts broken away and part in section. Fig. 2 is a horizontal sectional view of the same cut on the line 2—2 of Fig. 1. Fig. 3 is a detailed sectional view of a portion of the same. Fig. 4 is a plan view of a coil used in the furnace. Figs. 5 and 6 are detailed side elevations of igniting elements used upon the furnace. Fig. 7 is a sectional view of 25 the valve used upon the furnace, the view being cut on the line 7—7 of Fig. 2. Fig. 8 is a sectional view of the lower portion of a pump used in the furnace.

The furnace includes an outer tank 1 with 30 in which is located an inner tank 2. The outer tank 1 is provided with an opening 3 which is normally closed by a plug 4 and through this opening liquid fuel or oil may be introduced into the tank 1. The tank 2 35 is provided with an opening 5 normally closed by a plug 6. The said opening may be employed for admitting liquid fuel into the inner tank 2. A passage way 7 connects the upper portion of the tanks 1 and 2 and 40 is provided with a check valve 8 which when the air in the tank 1 arrives at a certain degree of pressure opens under the said pressure and permits the air to flow through the passage way into the tank 2. This valve includes a ball attached to a spring.

45 The means for creating air pressure in the tank 1 will now be described.

A cylinder 9 is supported from the top of the tank 1 and opens at its outer end above 50 the top of the said tank. The outer end of the said cylinder is normally closed by a cap 10. A check valve 11 is located at the lower end of the said cylinder 9 and controls the outlet of the said cylinder and also prevents

the oil from the tank 1 from flowing up into 55 the cylinder 9. A piston 12 is slidably mounted in the cylinder 9 and a stem 13 is connected with the piston and passes through the center of the cap 10. The stem 13 is provided at its upper end with a knob 14. A 60 spring 15 is located upon the stem 13 and when the piston 12 is drawn toward the cap 10 the ends of the spring 15 bear against the said cap and piston and cushions the movement of the piston toward the cap. Therefore it will be seen that by operating the 65 pump mechanism just described air pressure may be created in the outer tank 1 and when the said pressure reaches a certain degree it may force the valve 8 open and pass through 70 the passageway 7 into the inner tank 2.

Uprights 16 are mounted upon the top of the tank 1 and support at their upper end a plate 17. The said plate 17 is provided at its opposite edge portions with outstanding 75 lugs 18 with which may be detachably connected the end portions of a bail 19. The plate 17 is provided upon its upper side with ribs 20 and a shield 21 normally rests upon the upper side of the said plate and is held 80 in position thereon by means of the ribs 20. The central portion of the plate 17 is open. A hood 22 depends from the plate 17 and surrounds the central opening thereof. The said hood 22 is provided in its sides with 85 suitable openings and the bottom of the said hood is closed and a mat 23 of asbestos or other suitable material is located upon the bottom of the said hood.

A pipe 24 passes down through the top of 90 the tank 1 and terminates at its lower end in the vicinity of the bottom of the said tank although the lower end of the said pipe is spaced from the bottom of the tank. Above the tank 1 the pipe 24 is provided with a 95 controlling valve 25 of any suitable character. A —T— 26 is connected with the upper end of the pipe 24 and one of the branches of the —T— is closed by a plug 27. One end of a coil 28 is connected with 100 the other end of the said —T— and a section 29 of wire cord or rope is inserted in the end portion of the coil 28. This section may be placed in the coil by removing the plug 27 from the —T— 26 or by removing 105 the said plug the —T— may be connected directly with a source of gas supply. The coil 28 is formed with a series of convolu-

2

tions 30 which are approximately vertically disposed and centrally positioned within the hood 22. That end of the coil 28 which connects with the —T— is between the upper 5 and lower ends of the said series of convolutions. The uppermost convolution 30 of the series merges into a section 31 which is shaped like a figure 8 and which lies transversely across the central opening of the series of convolutions. From the said section 10 31 the end portion of the coil extends down exteriorly of the convolution 30 and is provided at its lower end with an —L— fitting 32. A nipple 33 is connected with the fitting 32 and is provided in its upper side 15 with an orifice 34 which is approximately centrally positioned with relation to the convolutions and the intermediate portion of the 8 shaped section 31.

20 A sleeve 35 is screw threaded upon the outer end of the nipple 33 and is provided upon its periphery with spaced flanges 36. A rasp 37 is located between the flanges 36. A shaft 38 is journaled in the sleeve 35 and the adjacent end portion of the nipple 33 25 and a stuffing box 39 of any approved character is mounted upon the said sleeve and is adapted to establish a tight joint between the sleeve and the shaft. The shaft 38 is provided at its outer portion with a coil 40 and the end portion of the said shaft extends back to the outer portion of the sleeve and is downwardly turned as at 41 and is provided with a pyrophoric element 42. 30 The turned end 41 is located between the flanges 36 while the sparking element 42 is held by the coil 40 resiliently against the rasp 37. Therefore the shaft 38 is constrained against longitudinal movement but 35 is free to be rotated. The inner portion of the shaft 38 which lies in the nipple 33 is flattened as at 43 and this flattened portion is located directly below the orifice 34, so that when the shaft 38 is rotated the said 40 flattened portion's edges will scrape the edges of the orifice and keep the same free from the accumulation of carbon or other obstructing material. The inner end of the shaft 38 is twisted as at 44 consequently 45 when the turned end 41 of the shaft is sprung from between the flanges 36 and the shaft 38 is moved longitudinally out of the nipple and sleeve the said twisted end will encounter any loose material such as carbon 50 and so forth which has been removed from about the orifice 34 and will drag the same out of the nipple and sleeve as the shaft is 55 withdrawn from the same.

It is obvious that when the shaft 38 is in 60 position in the sleeve and nipple and is turned, the sparking element 43 will have frictional engagement with the file 37 whereby sparks are created which ignite the gas fumes in the hood 22 as will be explained 65 presently.

A pipe 45 passes down through the top of the tank 2 and terminates in the vicinity of the bottom thereof. Above the top of the tank 2 the pipe 45 is provided with a controlling valve 46. The upper end of the pipe 45 communicates with the end of a pipe section 47, the intermediate portion of which is coiled about one of the uprights 16 and the said pipe section 47 passes through the side of the hood 22 and has its discharge 70 end located directly above the mat 23. The discharge end of the pipe 47 is disposed toward the sparking mechanism just above described.

The operation of the furnace is as follows: Presuming that the tanks 1 and 2 are under air pressure as above described the valve 47 is opened and the pressure of the air in the tank 2 will force the liquid fuel up through the pipe 45 past the valve 46 and up through the pipe section 47 into the hood 22 and upon the mat 23. An operator then revolves or turns the shaft 38 whereby a spark is created at the sparking element 42 and this spark ignites the liquid fuel just 80 introduced into the said hood. At this time or prior to this time the valve 24 is opened and the air pressure in the tank 1 forces the liquid fuel up through the pipe 24 past the valve 25 through the —T— 26 into the coil 28. The flame from the mat 23 and the lower portion of the hood 22 gasifies the oil thus admitted into the said coil 28. This gas passes down through the nipple 33 and thence through the orifice 34 and is ignited. 90 After this takes place the valve 46 is closed and the flame from the orifice 34 heats the coil 28 above. Thus as the oil is introduced into the coil it is gasified and passes from the upper portion of the coil down to the 100 nipple.

By reason of the fact that the inlet end of the coil 28 is located between the upper and lower ends of the set of convolutions 30 and the section 31 is located above the set of convolutions the upper portion of the coil 28 constitutes a trap or gasifying chamber inasmuch as the oil is admitted in the lower end portion of the set of convolutions and the gas passes up into the figure 8 section 115 110 115 and out through the orifice 34. By such an arrangement the oil is speedily converted from a liquid to a gaseous state and when the gas is liberated it is completely consumed whereby benefit can be had of all of the heat units contained in the fuel. For this reason the furnace is economical and efficient.

Having described the invention what is claimed is:—

1. In a furnace as described, a coil comprising a pipe formed with a series of convolutions, the admission end of the pipe being located between the ends of the said series of convolutions, the pipe being 130 125 130

formed above the convolutions with a section 8-shaped which lies transversely across the opening through the convolutions, the coil having an outlet below the convolutions.

2. In a furnace as described, a coil including a series of convolutions, an 8 shaped section located at the end of the convolutions and disposed transversely across the 10 openings through the set of convolutions, the coil having a discharge orifice positioned approximately centrally with relation to the convolutions and 8 shaped section.
- 15 3. In a furnace as described, a coil, a nipple connected with the coil, a sleeve connected to the nipple and having peripheral flanges, a file located between the flanges, a shaft journaled in the sleeve and nipple and having an edge portion disposed between the flanges and a sparking element carried by the said shaft and engaging the file.
- 20 4. In a furnace as described, a coil, a nipple connected with the coil, a sleeve connected with the nipple, a shaft journaled in the nipple and sleeve and having a flattened

inner end portion, said shaft projecting beyond the end of the sleeve.

5. In a furnace as described, a nipple 30 having in its side an orifice, a sleeve fixed to the nipple, a file carried by the sleeve, a shaft journaled in the sleeve and nipple and a sparking element carried by the shaft and engaging the file. 35

6. In a furnace as described a nipple provided in its side with an orifice, a sleeve attached to the nipple, said sleeve having upon its periphery flanges, a file located between the flanges, a shaft journaled in the 40 sleeve and nipple and having a flattened inner portion and a twisted inner end, said shaft being provided at a point beyond the sleeve with a coil, the other end of the shaft being disposed between the flanges 45 and a sparking element carried by the last mentioned end of the shaft and engaging the file.

In testimony whereof I affix my signature in presence of two witnesses.

ARTHUR J. ARCHAMBAULT.
